United States Patent Office

Des. 231,335
Patented Apr. 16, 1974

231,335

MOBILE FOOD PREPARATION UNIT

Ruth Allen, 199 St. Johns Place,
Brooklyn, N.Y. 11217

Filed Apr. 12, 1973, Ser. No. 350,472

Term of patent 14 years

Int. Cl. D15—08; D12—02
U.S. Cl. D12—22

FIG. 1

FIG. 2

FIG. 1 is a front perspective view of a mobile food preparation unit showing my new design; and

FIG. 2 bottom perspective view thereof.

The undisclosed rear is substantially a mirror image of the front.

I claim:

The ornamental design for a mobile food preparation unit, as shown and described.
